DYEING APPARATUS

Martin Karl, 333 Greenwich Ave., Warwick, R.I. 02886
Filed July 17, 1964, Ser. No. 383,348
4 Claims. (Cl. 68—27)

My present invention relates to the dyeing of textile materials such as yarns and raw stock, with particular reference to a novel apparatus for dyeing such materials.

The principal object of the present invention is to provide a dyeing apparatus for dyeing quantities of yarn and raw stock without felting and harshening.

A further object of the present invention is to provide an apparatus for dyeing yarn without the use of high pressure.

Another object of the present invention is to provide a novel apparatus for dyeing yarn and raw stock which is simple in construction and easy and economical to maintain, manufacture and assemble.

With the above and other objects and advantageous features in view my invention consists of a novel apparatus more fully disclosed in the details description following in conjunction with the accompanying drawings and more particularly defined in the appended claims.

In the drawings,

FIG. 1 is a side elevation of an apparatus embodying my invention.

FIG. 2 is a vertical section of one of the dyeing tanks.

FIG. 3 is a perspective view of the work holding baskets.

FIG. 4 is a plan view of the cover strip.

FIG. 5 is a perspective view of the baffle or divider.

In dyeing yarn it has been customary to place the yarn in a tank and circulate the dye water under high pressure and heat. This process tends to give a harsh and burned feeling to woolen or worsted yarns and raw stock.

The present invention is designed to overcome the above defects by providing an apparatus which dyes yarn and raw stock without high pressure. One of the features of the present invention is the passage of large quantities of the dye liquid through the material in a steady flow without high pressure using a circulating pump of the type shown in Patent No. 3,050,011 entitled Rotary Pump, issued August 21, 1962. The apparatus of the present invention also permits the reuse of the softened dye liquid which produces a very fine and even dyeing of the yarn.

Referring to the drawings, the apparatus comprises a pair of dyeing tanks 10 and 11 and a reserve tank 12 having a capacity equal to the combined tanks when loaded. The tanks 10 and 11 are connected adjacent their upper edges by an overflow or circulating section 13 which is approximately six inches in height and five inches in width. The tanks 10 and 11 are open at the top. At the bottom, the various tanks are connected by a series of pipes and valves for controlling the proper flow of liquid. A vertical pipe 14 extends from the bottom of the tank 10 and a similar pipe 15 extends from the bottom of the tank 11. The pipes 14 and 15 are connected by a horizontal pipe 16 controlled by a hand-operated regulating valve 17. This controls the free flow between the tanks 10 and 11. The pipe 15 is provided with a hand controlled valve 18 just below its connection with the pipe 16. The circulating system includes the circulating pump 19 which is of the type shown in the patent above referred to. One side of the pump 19 is connected through a pipe 20 to the bottom end of the pipe 14 extending from the tank 10. The other side of the pump 19 is connected through a pipe 21 to the reserve tank 12. A hand controlled valve 22 is positioned adjacent the tank 12 for controlling the flow of liquid to and from the tank. The pipe 21 is also connected at 23 to the valve 18 which

2

controls the flow to the tank 11. Intermediate the pump 19 and the connection 23 is a drainage connection 24 controlled by a manual valve 25. In addition a steam pipe 26, connected to a source of steam pressure, enters the tank 10 adjacent the bottom end, is looped in a semi-circle around the inside wall of the tank, exits at 27 and circles the inside of the tank 11, then returns at 28 back into the tank 10 around the inside wall and out at 29. The lines 26 and 29 are controlled by hand valves 30. The indirect steam lines above described are used for heating the liquid in the tanks 10 and 11.

The tanks 10 and 11 are identical in construction and are illustrated in more detail in FIGS. 2 to 5 inclusive. The size and capacity of the tanks may be varied by supplying tanks of larger dimensions. It is estimated that a 24 inch diameter tank, 32 inches in height will hold approximately 100 pounds of yarn.

The interior construction of each tank 10 and 11 is shown in FIG. 2. The body of the tank comprises a cylindrical member 31 having a bottom 32 and an open top. The tank can be made of any suitable material including aluminum to save weight and cost. Positioned on the bottom 32 is a baffle 33, shown in detail in FIG. 5. The baffle or divider 33 is mounted over the central inlet 25 of the pipe 14 in tank 10 and the pipe 15 in tank 11. It comprises a concave member 34 having spaced legs 35 which support the baffle in spaced relation to the inlet. On top, in the center of the concave portion 34 is a collar 36. In assembly a supporting rod 37 is set into the collar 36. The rod 37 is of such length that its top end will be about 5 inches lower than the top edge of the tank. A ring 38 is mounted on the bottom of tank 32. The ring 38 is approximately five inches in height and forms the rest for the baskets. The top edge is provided with a heavy lip 39 forming a thick portion. I now provide a plurality of work holding baskets 40, one of which is shown in FIG. 3. Each basket comprises an annular ring with a vertical wall of approximately five inches. The top is open and the top edge of the wall is provided with a heavy lip 41 which may be provided with three openings 42 for the insertion of lift hooks. The bottom of each basket is provided with a plurality of openings 43 and a large central opening 44. There are four 5" baskets which are placed one over the other so that the rod 37 extends through the central openings 44 with the bottom edge of each basket resting on the enlarged lip 41 of the basket below it. The top basket is covered by a perforated plate 45 and the entire assembly is covered by the cross member 46 shown in FIG. 4. The member 46 has four arms and the central opening 47 which slides over the rod 37. The entire assembly is now held down by a collar 48 having top and bottom flanges 49 which is slipped over the upper end of the rod 37. I now provide a lock in the form of a strip of metal 50 which extends as a diameter across the top of each tank and beyond the edges thereof. The central portion of the strip 50 bears downwardly on top of the flange 49 of the collar 48 to hold the baskets in place. The strip 50 is locked in position by means of a pair of pivoted bolts 51 mounted at diametrically opposite sides at the upper portion of the tank. The bolts 51 are pivoted into slots 52 at each end of the cover strip 50 and held in place by wing nuts 53.

The above construction permits the dyeing of two tank fulls of yarn simultaneously and the method of operation, with reference to the above construction is as follows:

(1) The virgin yarn or raw stock is laid into both tanks 10 and 11. This is accomplished by loading each basket 40 and lowering it into the tanks into the position shown in FIG. 2. At this time the machine is ready for the dyeing process.

(2) Dyestuff is boiled and dissolved in tank 12 with needed amount of water. With this completed, more cold water is added to cool dye liquid, and acid and other chemicals are added. At this point in the operation the drainage valve 25 has been shut. The valve 22 leading to the reserve tank 12 has been shut.

(3) The valve 18 leading to tank 11 is shut and valve 22 is opened. The pump 19 is started and thus starts dye liquid flowing into tanks 10 and 11. When dye liquid is all in the machine valve 22 is shut and valve 17 is opened for regulation of both tanks. The level of the water is brought to about two or three inches deep in the overflow portion 13.

(4) The valve 17 is shut and the valve 18 is now opened. Communication between the tanks 10 and 11 is now through the pump 19. This pump is designed to provide a maximum volume flow without surging and without high pressure. Note that the baffle plates 34 serve to divide the flow of water over the diameter of each tank. The water will surge upwardly through one tank, pass across the overflow portion 13 and down through the other tank. This circulation is reversed every three to five minutes by reversing the pump 19. The dyeing operation takes approximately two hours during which time the pump has circulated twelve to twenty times in each direction at three to five minute intervals an hour.

(5) When the pump is started up in step 4 the steam valve 30 is opened to heat the circulating dye liquid. The circulation of the steam is timed to slowly bring the temperature of the liquid to about 190-195° F. in approximately forty-five minutes and held at this temperature for the duration of the process.

(6) At the end of dyeing time, the steam is shut off. The liquid which is usually clear after the process can be pumped back into tank 12 for further use if desired. If this is not wanted, cold water will be added and drain valve 25 partly opened. The dyed lot is slowly cooled off until cold and clean.

This completes the dyeing operation in the tanks 10 and 11. The wing nuts 53 are removed and each basket is lifted out with the dyed yarn for the next step. New yarn is now positioned in the tank as in step 1. It will be found that some of the water has been evaporated and therefore the tanks are not completely full. Additional water is now added to fill the tanks to the proper levels. The entire cycle now proceeds as before. By reusing the original dye water much better results are obtained. I have found that the continuous use of the same water, if possible, aids in the even distribution of the dye and better handling of the material.

The above described apparatus thus permits the rapid and efficient dyeing of two tank fulls of yarn simultaneously in a single cycle. The dye water is gently circulated in volume in both directions providing for uniform even dyeing. The apparatus is simple in construction and easy and economical to assemble and operate. Other advantages of the present invention will be readily apparent to a person skilled in the art.

I claim:

1. An apparatus for dyeing textile materials comprising a pair of dyeing tanks, a reserve tank, an overflow circulating channel connecting said dyeing tanks adjacent the upper ends thereof, a conduit connecting the bottoms of said dyeing tanks, a second conduit connecting the bottoms of said dyeing and reserve tanks, a reversible high volume low pressure circulating pump in said second conduit, a steam line extending through the lower ends of said dyeing tanks, and manually operable valves in said conduits for controlling the flow of dye liquid between said tanks and said pump, each of said dyeing tanks having a baffle mounted on the bottom over said conduit inlet, a post extending vertically from said baffle, and a

plurality of stacked work holding baskets mounted around said post.

2. An apparatus for dyeing textile materials comprising a pair of dyeing tanks, a reserve tank, an overflow circulating channel connecting said dyeing tanks adjacent the upper ends thereof, a conduit connecting the bottoms of said dyeing tanks, a second conduit connecting the bottoms of said dyeing and reserve tanks, a reversible high volume low pressure circulating pump in said second conduit, a steam line extending through the lower ends of said dyeing tanks, and manually operable valves in said conduits for controlling the flow of dye between said tanks and said pump, each of said dyeing tanks having a baffle mounted on the bottom over said conduit inlet, a post extending vertically from said baffle, and a plurality of stacked work holding baskets mounted around said post and means for locking said baskets in said tanks.

3. An apparatus for dyeing textile materials comprising a pair of dyeing tanks, a reserve tank, an overflow circulating channel connecting said dyeing tanks adjacent the upper ends thereof, a conduit connecting the bottoms of said dyeing tanks, a second conduit connecting the bottoms of said dyeing and reserve tanks, a reversible high volume low pressure circulating pump in said second conduit, a steam line extending through the lower ends of said dyeing tanks, and manually operable valves in said conduits for controlling the flow of dye liquid between said tanks and said pump, each of said dyeing tanks having a baffle mounted on the bottom over said conduit inlet, a post extending vertically from said baffle, and a plurality of stacked work holding baskets mounted around said post, each of said baskets comprising an annular wall portion and a perforated bottom, the top edge of said wall portion having a heavy bead for supporting the next vertical basket.

4. An apparatus for dyeing textile materials comprising a pair of dyeing tanks, a reserve tank, an overflow circulating channel connecting said dyeing tanks adjacent the upper ends thereof, a conduit connecting the bottoms of said dyeing tanks, a second conduit connecting the bottoms of said dyeing and reserve tanks, a reversible high volume low pressure circulating pump in said second conduit, a steam line extending through the lower ends of said dyeing tanks, and manually operable valves in said conduits for controlling the flow of dye liquid between said tanks and said pump, each of said dyeing tanks having a baffle mounted on the bottom over said conduit inlet, a post extending vertically from said baffle, and a plurality of stacked work holding baskets mounted around said post, each of said baskets comprising an annular wall portion and a perforated bottom, the top edge of said wall portion having a heavy bead for supporting the next vertical basket, and means for locking said baskets in said tanks.
